CLAIM

The ornamental design for the removable tray on a walker with rollers, as shown and described.

DESCRIPTION

FIG. 1 is a front-elevational view my novel removable tray on a walker with rollers;

FIG. 2 is a rear-elevational view thereof;

FIG. 3 is a top-plan view thereof;

FIG. 4 is a bottom-plan view thereof, showing a spring-loaded, releasable clamp for fastening the tray to the walker;

FIG. 5 is a side-elevational view thereof; and,

FIG. 6 is a top-plan view of the tray with a second embodiment of a support surface; the bottom view of the second embodiment being identical to FIG. 4.
